CLAIM

The ornamental designs for an abdominal contact pad for an abdominal exercising apparatus, as shown and described.

DESCRIPTION

FIG. 1 is a perspective view of an abdominal contact pad for an abdominal exercising apparatus, showing my new design, wherein the broken line showing of the abdominal exercising apparatus is for illustrative purposes only and forms no part of the claimed design;

FIG. 2 is a top plan view thereof;

FIG. 3 is a side view thereof;

FIG. 4 is a front thereof;

FIG. 5 is a rear view thereof; and,

FIG. 6 is a bottom view thereof.
